UNITED STATES PATENT OFFICE

122,673

DESIGN FOR A CASE FOR CLOCKS OR SIMILAR ARTICLES

William K. Sessions, Forestville, Conn., assignor to The Sessions Clock Company, Forestville, Conn., a corporation of Connecticut

Application July 31, 1940, Serial No. 94,057

Term of patent 14 years

To all whom it may concern:

Be it known that I, William K. Sessions, a citizen of the United States, residing at Forestville, in the county of Hartford and State of Connecticut, have invented a new, original, and ornamental Design for a Case for Clocks or Similar Articles, of which the following is a specification, reference being had to the accompanying drawing, forming part thereof.

Fig. 1 is a perspective view of a case for clocks or similar articles showing my new design; and Fig. 2 is a view thereof in edge elevation.

The characteristic feature of my design resides

in the case having complementary end panels at each side of the main body of the case. The said complementary panels having their tops curved downwardly and away from the main body of the case, and which panels also have their vertical portions curved rearwardly and away from the said main body, and the two said curved portions merging.

I claim:

The ornamental design for a case for clocks or similar articles, substantially as shown and described.

WILLIAM K. SESSIONS.
